[57] CLAIM

The ornamental design for an egg carton, substantially
as shown and described.

DESCRIPTION

FIG. 1 is a front perspective view of an egg carton
showing my new design;

FIG. 2 is an end elevational view showing the end
opposite that seen in FIG. 1;

FIG. 3 is a top plan view;

FIG. 4 is a sectional view on the line 4—4 of FIG. 3;

FIG. 5 is a bottom plan view;

FIG. 6 is a top plan view with the lid in an open
position;

FIG. 7 is a bottom plan view with the lid in an open
position;

FIG. 8 is a rear perspective view; and

FIG. 9 is a fragmentary perspective view showing the
interior of the bottom half of the egg carton.
